STABILIZING HARNESS FOR SUSPENSION BRIDGES

Merl R. Wolfard, Cambridge, Mass.

Application February 6, 1945, Serial No. 576,394

20 Claims. (Cl. 14—19)

1

This invention relates to stabilizing harness for principal load-sustaining elements that hang with sag in suspension bridges.

More particularly it relates to the stabilizing of load-sustaining elements that hang with approximately parabolic sag to sustain dead load at many points between supports, and are subject to intermittent live loadings which tend to produce undulatory movements of those elements, as in the cables of suspension bridges.

The invention provides a stabilizing harness which is connected to a principal load-sustaining element at a plurality of spaced-apart points along that element. The harness, when the principal element is static, deflects that element upward at one harness-connected point and downward at an adjacent harness-connected point. There should be at least one such upward deflection and one such downward deflection of the principal element in each end-half portion of a span. Usually there will be not less than three spaced-apart harness-connected points in each end-half portion of the span of a principal element between its supports.

A principal element, in which the undulatory movement may occur, may have a degree of resistance to bending, indeed the large cables required for long suspension bridges have very substantial resistance to localized bending. Such stiffness may be sufficient to resist localized deflections resulting from live loadings, without being sufficient to prevent the longer undulatory movements which intermittent winds and moving loads may produce. These longer undulations are transmitted to the bridge platform, and, if not arrested, become detrimental and even destructive. The currently accepted method of restricting such undulations is to add a stiffening girder. Such girders are both massive and expensive. The stabilizing harness of this invention, in comparison, is light and inexpensive, yet it arrests all such undulatory movements without the use of a stiffening girder.

This unique effect depends upon the locations of the harness connections to the principal load-sustaining element, and upon the oppositeness of the directions in which the harness restrains movements of that element at those connections. The upward and downward deflections of the principal element at the harness-connected points need not be great. It is an outstanding discovery that the harness of this invention thus connected is effective in arresting lengthwise travel of undulations along the principal element. Intermittent deflections resulting from localized live load-

2

ings do not become communicated to remote parts of the principal element. And the opposing restraints applied by the harness to that element are such that no single gust of wind is sufficient to initiate a general travel of undulation along the principal load-sustaining element. Therefore successive gusts cannot build up large undulations of that element.

The stabilizing effectiveness of the harness has been established by an extensive series of experiments with models of different sizes employing materials having a high modulus of elasticity in various structural arrangements.

In the absence of a theoretical analysis adequate to explain fully the remarkable results obtained, the following observations are helpful for visualizing the nature and effect of the forces which may act, concomitantly or successively, at the harness-restrained points.

20 In any vibrating structure forces resulting from resilience of the elements of that structure are factors that contribute to the building up of whatever large undulations occur. The high tension materials used in suspension bridges are particularly active resiliently. It seems probable that the separating of points at which restraining forces may act in opposite directions, concomitantly with resilient forces that are out of phase with at least one of those oppositely acting forces, 25 is of vital import here, the resilient forces of the ties being in the directions of the lengths of those ties while the concomitantly acting resilient forces of the principal load-sustaining element are primarily crosswise of the length of that element. Furthermore, rhythmic undulations of the structure are inhibited by the lengthwise elements of the harness being loaded at fewer points than is the co-extensive lengthwise portion of the principal element.

30 In previous structures where restraint has been applied at each of a series of points in an effort to reduce undulations, as in a truss, the restraint has been applied in more than one direction, usually in opposing directions at each point of the series. This tends to fix each point and makes each point able to become a nodal point in undulations of the structure.

35 By providing forces acting in opposite directions crosswise of the principal element, at points spaced-apart from each other along that element, the harness restrains and arrests undulatory movements of the principal element. This is without providing points at which nodes become readily established. Since undulatory movements occur relative to nodal points, the apply-

ing of restraint without making points readily available to become nodes prevents the developing of large detrimental waves in the bridge structure.

In suspension bridges having long spans the required size of each cable provides a stiffness which is sufficient to resist local deflections that result from intermittent live loadings; and so undulations of the shorter lengths are prevented. In shorter spans, where the requisite size of the cable does not make the cable be stiff enough, the invention provides a special cross-sectional distribution of area for the load-sustaining element which stiffens that element in those regions of its length which are between the harness-connected points. Thereby, the usual stiffening girder is eliminated from such spans. Furthermore, spans that are shorter than have heretofore been deemed feasible for suspension bridges can be built, with much less material and with greater stability than if a truss type of structure having equal length of span were used.

In this special distribution of cross-sectional area the lower tension-carrying area is many times larger than its upper area which carries compression. This saves much material in comparison with the using of an I-beam.

For cases where it is desirable that the anchorages of the principal element should be not beyond the end of the span, a compression member may be provided extending from one supported end of the principal element to the other. The principal load-sustaining element preferably has the special cross-sectional area mentioned above.

It is intended that the patent shall cover by suitable expression in the appended claims whatever features of patentable novelty exist in the invention disclosed.

The accompanying drawings are diagrammatic, and the proportions of some parts are distorted, showing.

Figure 1 is a side elevation showing the harness of the invention applied to a suspension bridge of usual type in which the principal load-sustaining element is a cable, and there is an upper tension element of the harness extending co-extensively with the cable;

Figure 2 is a side elevation of another suspension bridge, in which the load-sustaining element is of inverted-T cross-section, and in which the upper tension elements of the harness are not co-extensive with the principal element but extend only from one harness-connected point to a remote harness-connected point;

Figure 3 is a side elevation of the central span of still another suspension bridge in which the invention is embodied in a harness of very few parts;

Figure 4 is a side elevation of a suspension structure, in which there is a compression member between the ends of the load-sustaining element;

Figures 5 and 6 are respectively a side elevation and an end elevation in cross-section of an I-beam, with descriptive reference lines;

Figure 7 is an end elevation showing a preferred form of distributed cross-sectional area of a load-sustaining element, being a modified T-cross-section inverted; and

Figure 8 is an end elevation in cross-section showing a composite structure for a stiffened load-sustaining element.

In the drawings, Figure 1 shows how the principles of the invention may be applied for stabilizing a suspension bridge in which the principal

load-sustaining element is a cable, such as is commonly used, this being the preferred construction for a suspension bridge having a long span.

The cable 10 is suspended between towers 12 and extends through side spans to anchorages 14. Hangers 16 depend from the cable 10 supporting the platform 18 as is usual.

The stabilizing harness of the invention as represented in Figure 1 comprises an upper tension element 20 co-extensive with the cable 10, and has anchorages 15 at each end which are substantially below the respective anchorages 14 of the cable. The stabilizing harness comprises this upper tension element 20 combined with a lower tension element 22 extending along a midportion of the span, at the middle of which is a clamp 26 to prevent endwise slipping relative to the upper tension element 20. The lower element 22 extends lengthwise downwardly to the cable 10 to which it is connected at points 23 within the middle-half-portion of the span. Intervening between clamp 26 and each point 23 there is a strut 24 between the lower tension element 22 and the cable 10. This strut bends the tension element 22 upwardly, and applies a downward deflection to the cable at the point 25 at the bottom of the strut. This provides an upward deflection of the cable at 23 at each end of the tension element 22 and a downward deflection of the cable at each point 25 which is at the bottom of a strut 24 on each side of the center of the span.

The harness illustrated in Figure 1 also comprises ties 28, one in each end-quarter-portion of the span, causing a downward bend in the upper tension element 20 which applies an upward deflection to the cable 10 at the point 29 of connection. In Figure 1 the harness also has a tie 30 in each side span which applies a downward bend to the side-span portion of the upper tension element 20 and applies an upward deflection to the cable 10 at 31.

Between this point 31 and the anchorage 14 of the cable the upper tension element 20 of the harness crosses the cable 10, in each side span at a distance from its anchorage 15 which is substantially lower than the anchorage 14 of the cable 10, and at the point 33 near the crossing there is a tie 32. Thereby an upward bend is provided in the upper tension element 20, which produces a downward deflection of the cable 10 at the point 33.

In Figure 1 the harness also has a plurality of ties extending from appropriate points in each tower 12 to points in the side spans and in the adjacent end-quarter-portion of the center span. In this particular illustrative diagram there are four of these ties, 34, 36, 38 and 40, connected to the cable 10 respectively at points 35, 37, 39 and 41, and applying to the cable a downward deflection at each of these points. The points 35 and 37 are on opposite sides of the upwardly deflected points 31. The points 39 and 41 are on opposite sides of the upwardly deflected points 29.

Figure 2 shows a harness embodying the invention in which the upper lengthwise tension elements of the harness are not co-extensive with the load-sustaining element. This figure illustrates the use of an inverted-T cross-section, of

which Figure 7 is an example, which provides for localized stiffness between the harness-connected points whose movements are restrained by the harness. In Figure 2, the load-sustaining ele-

ment 110 extends from the center span over the towers 112 and through the side spans to anchorages 114. It supports a platform 118 by hangers (not shown) which may be of usual style. The harness in Figure 2 comprises lengthwise harness elements 50 which are only in the center span and extend from a point 49 and an end-quarter-portion of the center span of element 110 to a harness-connected point 51 in the third-quarter-portion of the same span, counting from the same tower. Intervening between point 51 and the mid-point of the span there is a strut 54 between the harness element 50 and the principal load-sustaining element 110 beneath it. The top of the strut 54 bends the harness element 50 upwardly, thereby providing a downward deflection of the load-sustaining element at the point 55 at the bottom of the strut. In the load-sustaining element 110, from points 59, 61 in opposite directions from each harness-connected point 49, each of which applies upward deflection, ties 58, 60 extend downwardly to the adjacent tower and each apply downward deflection to the load-sustaining element 110.

The structure thus described with reference to Figure 2, even though having only one of the two pictured harness elements 50, is sufficient to apply to the load sustaining element 110, a substantial stabilizing influence which, except under extreme conditions, is adequate to prevent the travel of undulation along the principal element, that is, to prevent travel from a non-harnessed portion of the principal element, through that portion of the span where the harness-restrained points are, to another portion of the principal element. Undulations arising in a non-harnessed part of the structure will be arrested in the harnessed part. Obviously the stability of the structure as a whole would be improved by having two harness elements 50, with their associated elements as described, and as illustrated in Figure 2 in the center span.

I have demonstrated by experiments that the overall stability of a suspension bridge having side spans depends in large measure upon the stability of those side spans. In engineering discussions of the undulation of suspension bridges resulting from the impact of winds it has been recognized that the greatest disturbances are caused by quartering winds, without the reason being known, so far as I am aware. I have discovered, and have demonstrated by experiments, that a force acting intermittently and having a component lengthwise of the bridge very readily sets up vibrations of the whole bridge in which the undulations extend the whole length of the bridge. In fact I have demonstrated that a light lengthwise force applied intermittently and rhythmically at the top of one tower only of a bridge of conventional type is sufficient to set up violent undulations throughout the whole length of the principal load-sustaining elements if they are not adequately stabilized. The applying of the harness of this invention to these load-sustaining elements, and extending the harness through the side spans eliminates such undulations.

In Figure 2 an element of the harness is applied to the side spans by providing upward extensions 113 of the towers 112, above the level where the load-sustaining element 110 is supported by those towers 112; and there is a tension element 70 of the harness running downwardly from the top of this extension to an anchorage 116 above the anchorage 114 of the chain 110. A tie 72 con-

ncts a mid-portion of this element 70 to the principal element 110 beneath it at a point 73 in that element. The downward bend in the tension element 70 at the tie 72 provides an upward deflection of the principal element 110 at the point 73. In the side span, in opposite directions from the point 73, there are harness-connected points 75 and 77. From the point 75 a tie 74 extends downwardly to a lower part of the tower 112. From the point 77, the tie 76 extends downwardly to an anchorage 115 which is substantially below the anchorage 114 of the element 110. The ties 74, 76 provide downward deflections in the element 110 on opposite sides of the upward deflection therein at the point 73.

Figure 3 shows the center span only of a suspension bridge having a load-sustaining element 210 extending over and supported by towers 212 and carrying a platform 218 by hangers (not shown) which may be of usual type. This illustrates the simplicity with which the invention can be constructed, having in each end-half of the span only three harness-connected points, which in some cases will suffice.

25 There is an upper tension element 220 of the harness which extends from a point 229 in the load-sustaining element 210, near one tower to another point 231 in that element near the other tower. There is a lower lengthwise harness element 30 which extends from a point 223 in the load-sustaining element 210 across the mid-portion of the span to a point 227 in that element, each of these points 223, 227 being at distances in opposite directions from the center of the span. 35 The harness elements 220 and 222 are clamped together at the mid-portion of the span as by a clamp 226, which clamp should be sufficiently secure to prevent end-wise slip of these two elements relative to each other.

40 The point 223 is below a projection (dotted in Figure 3) of a straight index line extending from the point 231 to the clamp 226. Likewise the point 227 is below a projection of a straight index line extending from the point 229 through the 45 clamp 226.

By this arrangement when a live-loading becomes incident on the principal element 210 near the point 223 there will be a resulting tendency to pull the clamp 226 downwardly, thereby relaxing that portion of the harness element 222 which extends to its connection 227 in the load sustaining element 210. Thereby that part of the dead load, imposed on that element 210 at the region of the point 227, and carried, when the 55 load-sustaining element 210 is static, by the harness element 222 extending from that point to the clamp 226, is relieved by that live loading. The loading thus relieved is available to minimize the tendency to rise at the point 227 which is caused by the incidence of the live loading at the point 223. While the shift in loading may be not large it is in the direction which opposes rhythmic undulation of the element 210.

The structure shown in Figure 2 is operative 65 without there being a clamp at the center of the span holding the harness elements 50 against lengthwise slip relative to each other; but optimum stabilization for a given weight of material is obtained by using such a clamp, as illustrated 70 in Figures 1 and 3. If such a clamp is embodied in the structure of Figure 2 the locations of the points where the harness elements 50 are connected to the load-sustaining element 110 within the mid-half-portion of the span should also 75 preferably be below a straight index line, as de-

scribed with reference to Figure 3, and as is seen in Figure 1.

In Figure 3, in each end-half-portion of the span, between the points 229 and 223 at one end-half, and between 227 and 231 at the other end-half, there is a point 239, 249, from which a tie 238, 248, extends downward to a fastening on the adjacent tower, which as shown in this Figure 3 is below the platform 218. One of these ties 238 produces downward deflection of the load-sustaining element 210 at the point 239, and that element is deflected upwardly at the harness-connected points 229 and 223 by the harness-elements 220 and 222 respectively. Likewise the other tie 248 produces downward deflection of the load-sustaining element 210 at the point at 249 intermediate of the upward deflections of that element produced by the harness at the points 227, 231.

Figure 4 illustrates a new type of bridging structure that the invention makes possible by placing a compression member 302 between the ends of the principal load-sustaining element 310, at the tops of the end supports 312. These supports preferably are inclined inward of the span as indicated. A number of hangers 316 depend from the load-sustaining element 310 to support the platform 318. The compression member is set with a bend upwardly at the points 303, one of which is in each end portion of the span, which provides an upward thrust at each bend 303. There are ties 304 extending downwardly from the points 303 to the load-sustaining element 310 and providing upward deflections of that element 310 at the points 305. Located between each point 305 and at the end connecting points of the compression member 302 to the load-sustaining element 310, there is a point 307 in the load-sustaining element 310 from which the tie 306 extends downwardly and outwardly to the lower end of its nearer support 312, which provides a downward deflection of the load-sustaining element 310 at the point 307. In the region of a quarter length of the span from each end there is a strut 322 extending between and connected to the load-sustaining element 310 and the compression member 302. There are cross ties 332 extending each from the compression member 302 at the top of one of these struts 322 obliquely downward to a point 333, 333 in the load-sustaining element 310 at a substantial distance from and short of the bottom of the strut 322 which is toward the other end of the span. The tensions in each of these ties provides an upward deflection of the element 310 at its respective point 333. The same tension provides the downward load on the strut 322 at whose top it is connected, thus applying a downward deflection to the element 310 at the bottom of that strut. Preferably the cross ties are clamped together by a clamp 336 where they cross at the middle of the span. There is a tie 334 extending downwardly from the clamp 336 to a point 335 in the mid-portion of the principal load-sustaining element 310. Tension in this tie provides upward deflection in that element at that point 335. There are also spacing struts 324 extending each from a point 325, located between the points 333 and 335 in the element 310 extending upwardly to the compression member 302. These struts carry the weight of the mid-portion of the compression member 302 and therefore provide a downward deflection at their bottom ends 325.

The platform 318 is supported at many points

by the hangers 316 without the heavier dead loadings and live loadings being transmitted from the platform to the compression member 302. Thereby the heavy inclined bracings which are an essential part of a truss as usually constructed are eliminated. This elimination of the need of transmitting heavy forces up to and back from a top chord not only dispenses with the long heavy inclined struts needed to transmit those forces but also saves the added weight required to stabilize the whole truss because of their great weight.

For the structure of the principal load-sustaining element, a cable is preferable, if the span is long, because in a long span the size required, 15 for carrying the total tension load only, is sufficient to provide a satisfactory localized stiffness of the load-sustaining element between the spaced-apart harness-restrained points. In 20 shorter spans the size of cable required merely for carrying the tension load may be not sufficient to produce the desired stiffness between the spaced-apart harness-restrained points. In such 25 shorter spans it is desirable to provide a distribution of material which produces the required resistance to bending with a minimum of weight of material.

If the load-sustaining element is a bar of T-cross section, used with the stem of the T upward as indicated in section in Figure 7 and in side elevation in Figures 2, 3 and 4 (where the vertical extent of the bar relative to its length is exaggerated), the required stiffness between the harness restrained points is obtained, from 30 the stem of that T, with the use of much less material than if the element were of the usual I-beam cross-section. Figures 5 and 6 being a side and an end elevation of an I-beam illustrate one reason for this. The dotted line 350 35 represents the neutral axis at the mid-height which, in engineering calculations as to stiffness, is supposed to remain at that position. This results because the total loading of a beam is assumed to be at right angles to its axis. However 40 in an I-beam used to fulfill a two-fold function, as an element sustaining load by pull at its ends and as a beam, the tension load due to the pull becomes added to the lower flange of the I, and the neutral axis moves upward as the ratio of 45 the total load carried by tension increases relative to the load carried by compression in the upper flange of the I, i. e. the effective beam-depth diminishes as the ratio of the tension load to the compression load increases. This is indicated graphically by the upper broken line 352 50 in Figures 5 and 6. In extreme cases the bending resistance is only that of a flat bar represented by the upper flange. But in contrast to this, by the invention, material that might be in the upper flange of the I-beam is redistributed 55 into the vertical stem of the inverted T. Therefore a given amount of material distributed as in Figure 7 is advantageously distributed in the load-sustaining element to combine with the stabilizing harness to approach an optimum of 60 stability with a minimum weight of material in a load-sustaining element as in Figures 2, 3 and 4. In such a combination the principal element is restrained against large undulatory movements 65 at spaced-apart points with which the harness is connected, so that no large tension load can ever be imposed upon the upper end of the stem of the T, which is normally under compression; and the resistance of such a principal element to 70 localized bending between the harness-connected 75

points is sufficient to provide for whatever stiffness is required for avoiding localized undulations in the platform which is supported by the hangers between those points. The static location of the principal element, at least in those sections which are between the harness-restrained points, should be such that substantial compression stress exists in the upper part of the cross-sectional area of such an element, i. e., its curvature before assembly should be less than the curvature is when it is in assembled position; thereby the curvature in the assembled position will be less than parabolic for that section of the element which is between harness-restrained points.

This structure possesses many practical advantages over the usual truss alone, or a suspension bridge having its load sustaining element stabilized by stiffening girders. It results in great savings in cost, as well as improved stability in spans which are much shorter than have hitherto been considered practicable for bridges of suspension type, because of the cost of required stiffening girders.

The essential characteristic here is that the lower tension carrying area of the principal element shall be much greater than the upper area which carries compression.

Figure 8 shows a composite structure of this type for a principal element in which tension-carrying capacity is afforded by flat steel bars 360 in the form of ribbons beneath the flange 364 of a modified T 362 at the top of whose stem there is a larger rounded section 366. This has special utility for spans of intermediate length, longer than those for which the integral cross-section of element shown in Figure 7 would be suitable, and shorter than those spans in which the size of cables required for sustaining only the tension loads would be too small to produce the desired localized stiffness between the harness-restrained points. In constructing such spans these ribbons may individually be drawn over the towers, and a stiffening bar 362 placed on top of a pile of such ribbons as indicated in Figure 8, all being later bound together as may be desired.

In structures stabilized according to the invention the magnitudes of the deflections at the harness-restrained points may ordinarily be small, and their upward or downward displacements from the true parabolic location of the principal element need not be equal. In fact, where there are two deflections in one direction and one in the opposite direction between those two, the displacement from the true parabolic position may be greater in the direction in which the two deflections occur, or vice versa. The stabilization appears to reside more in the oppositeness of the displacements than in the equality of such displacements from the true parabolic position of the element when that element is static. Throughout this description the upward and downward deflections of the load-sustaining element designate deflections which are present relative to each other when the element is static.

Where an upward deflection intervenes between two downward deflected points the harness will preferably be arranged to deflect the element below its true parabolic static position, even at the intervening upwardly deflected point, i. e., the upward deflection is relative to the points between which it intervenes.

The amount of deflection at the downwardly

deflected points, particularly in the end-quarter-portions of the span, should be such that the normal traffic loading on the bridge will not cause further deflection. That is, if the tensions in ties which produce the downward deflections apply a static load about equal to the expected live loading, then the bridge will be exceedingly stable for that traffic; and these ties will not produce a continuous excessive stressing of the load-sustaining element because the static loading by such ties disappears when the expected live loading becomes incident, relaxing the ties. Deflections caused by traffic loadings heavier than normal, beyond the measure to which the particular installation is adapted, as when a heavier-than-normal truck passes over a highway bridge, may pass the limits at which optimum stability is attained without harm to either the load sustaining elements or the harness elements.

As to the upward deflections, it is observed that a degree of stabilization appears when the upper tension elements of the harness become taut enough to initiate upward deflections. The stability increases with increased stress in these harness elements, up to a magnitude which provides an upward force which is well below the downward force described as preferable for downwardly deflected points of the principal element. Increasing the stress beyond that up to the full magnitude of the said forces supplied to the downwardly deflected points makes no apparent change in the stabilizing characteristics.

It will be understood that the tension elements 35 of the harness and the ties herein described each may have any suitable means for adjusting its tension, as, e. g., a turnbuckle, representations of such adjusting means being omitted from the drawing in the interest of clarity, being well known in the art. Also the various described deflections of the principal load-sustaining element at the harness-connected points are omitted from the drawing, these being so small relative to the general curvature that their graphical representation in the figures of this drawing would distort the visual appearance from the true aspect of the load-sustaining element more than does the showing of that element undeflected from its parabolic position.

50 The harness-connected points in the load-sustaining element need not be at uniform distances apart along that element, indeed some dissimilarity in distance is advantageous because it aids in preventing the development of nodes at uniform distances apart along the element. For example, in Figure 1 the points 29 and 41 are closer together than the points 41 and 23. The points 23 and 25 are closer together than the points 25, 55 25 on opposite sides of the center of the span, and also closer together than the points 23 and 41 in the opposite direction from the point 23. The distance between the points 23 and 41 may be relatively greater than is shown in the drawing as compared with the adjacent points 25 and 29.

60 65 Bridge engineers recognize that a suspension bridge may be suitably stable for traffic and may nevertheless be susceptible to large undulations, caused by winds. The problem of preventing such undulations is the subject of extensive research, but so far as I am aware no satisfactory solution for the stabilization of existing bridges has yet been found. The stabilizing harness of the present invention provides a simple and inexpensive method for stabilizing such bridges.

against wind disturbances. The restraints provided by this harness are such that the maximum impact by a single gust of wind is unable to initiate a general travel of an undulation along the principal load-sustaining element and bridge. In consequence the larger undulations which are detrimental and even may become destructive cannot be built up. The effectiveness of the general restraint which the harness imposes on the bridge structure appears to stem from the simple fact that no localized displacement resulting from intermittent loadings can be transmitted toward the remote parts of the load sustaining element without being diminished, retarded and arrested.

I claim as my invention:

1. Means for controlling undulatory movements of a load-sustaining principal element which is anchored at its ends and hangs with sag to sustain dead load at many points between supports by tension stress existing at least in the lower portion of said element and which stress is transmitted as a tension force to the end anchorages, said principal element being subject to intermittent live loadings which tend to produce undulations of that element, said means comprising, in combination, a stabilizing harness having harness elements which are connected to that principal element from above the principal element and from below the principal element at points which are spaced apart along the principal element, each said harness connection being the controlling restraint at its particular point of the principal element; and that principal element, when it is static, being thereby at one said point deflected upward and at an adjacent said point deflected downward; there being a plurality of said harness-connected points in each end-half-portion of said principal element between said supports, and there being at least one said upward and one said downward deflection of the principal element at adjacent harness-connected points in each end-half-portion of the span between said supports.

2. Means as in claim 1 for controlling undulatory movements, in which the harness-connected points include a series of three of such points in each said end-half portion of the said principal element, in each of which said series the deflection at the intermediate point is opposite in direction from the deflections at the other two of the three said points of the series.

3. Means as in claim 1 for controlling undulatory movements, in which the harness-connected points include a series of three of such points in at least one end-quarter-portion of said span, in which said series the deflection at the intermediate point is upward and the deflections at the other two of the three said points of the series are downward; and, in the third-quarter-portion of that span, there is a said upward deflection and a said downward deflection which are at adjacent harness-connected points.

4. Means as in claim 1 for controlling undulatory movements, in which the said harness-connected points include a series of three of such points in each end-quarter-portion of the said principal element between said supports, in each of which said series of points the deflection at the intermediate point is upward and the deflections at the other two of the three points in that series are downward.

5. Means for controlling undulatory move-

ments of a load-sustaining principal element which is anchored at its ends and hangs with sag to sustain dead load at many points between supports by tension stress existing at least in the lower portion of said element and which stress is transmitted as a tension force to the end anchorages, said principal element being subject to intermittent live loadings which tend to produce undulations of that element, said means comprising, in combination, a stabilizing harness having an upper harness element extending lengthwise of said span above said principal element and connected to that principal element within each end-quarter portion of the span; and another harness element which is located between the said upper harness element and the principal element, having its ends connected to the principal element at junction points which are within the middle-half-portion of the span, the mid-portion of this other harness element being clamped to the upper harness element so as to prevent lengthwise slip relative to that upper element; and, in each end-portion of the span, at least one tying element connected to the principal element at a location which is spaced apart from the connection of said upper element in that end-portion of the span; these tying elements being each inclined downwardly, and being fast to the nearer end support, and providing a downward deflection of the principal element; the harness elements which are connected from above providing upward deflections of the principal element; the said deflections being provided when the principal element is static.

6. Means as in claim 5, for controlling undulatory movements, in which the said junction points are each below a projected straight index line extending from a connection of the upper harness element to the principal element in an end-quarter portion of the span through the location where the said upper and other harness elements are clamped together.

7. Means as in claim 5, for controlling undulatory movements in which there is a strut located intermediate of each said junction point and the clamp, between the principal element and the said other harness element, bending upwardly that other harness element and providing a downward deflection of the principal element at the lower end of each said strut.

8. Means as in claim 5 for controlling undulatory movements, in which the said junction points are each below a projected straight index line extending from a connection of the upper harness element to the principal element in an end-quarter portion of the span through the location where the said upper and other harness elements are clamped together; and there being a strut located intermediate of each junction point and the clamp, between the principal element and the said other harness element, bending upwardly that other harness element and providing a downward deflection of the principal element at the lower end of each said strut.

9. Means as in claim 5 for controlling undulatory movements, in which, in each end portion of the span a connection of a said tying element from below intervenes between the connections of a said upper element and a said other element to the principal element from above.

10. Means as in claim 5 for controlling undulatory movements, in which there are two said tying elements connected to the principal element from

below, in each end portion of the span, between which two the said connection of the upper harness element to the principal element intervenes.

11. Means as in claim 1 for controlling undulatory movements, in a structure in which the said supports are towers over which the said principal load-sustaining element extends through side-spans to the said anchorages; in which the harness elements comprise an upper element extending also between and over those towers and through side-spans to anchorages, this harness element being above the principal element between the towers and throughout at least a portion of each side span; there being in each end-quarter-portion of the span between the towers a tie connection of said harness element to the principal element, thereby providing said upward deflections of the principal element; and there being a tie connection of the harness element to the principal element at a mid-location in each side-span, providing there an upward deflection of the principal element.

12. Means as in claim 1 for controlling undulatory movements, in a structure in which the said supports are towers over which the said principal load-sustaining element extends through side-spans to the said anchorages; in which the harness elements comprise an upper element extending also between and over those towers and through side-spans to anchorages, this harness element being above the principal element between the towers and throughout at least a portion of each side span; there being in each end-quarter-portion of the span between the towers a tie connection of said harness element to the principal element, thereby providing said upward deflections of the principal element; and there being a tie connection of the harness element to the principal element at a mid-location in each side-span, providing there an upward deflection of the principal element; said upper harness element crossing the said principal element in each side-span at a substantial distance from the anchorages, and there being connecting means at that crossing; the anchorages of said harness element being substantially below the respective anchorages of said principal elements, thereby providing downward deflection of the principal element at said connecting means at the crossing.

13. Means as in claim 1 for controlling undulatory movements, in a structure in which the said supports are towers over which the said principal load-sustaining element extends through side-spans to the said anchorages; in which the harness elements comprise an upper element extending also between and over those towers and through side-spans to anchorages, this harness element being above the principal element between the towers and throughout at least a portion of each side span; there being in each end-quarter-portion of the span between the towers a tie connection of said harness element to the principal element, thereby providing said upward deflections of the principal element; and there being a tie connection of the harness element to the principal element at a mid-location in each side-span, providing there an upward deflection of the principal element; there being also within each side-span ties connected to the principal element, extending downwardly obliquely to the tower, providing downward deflections of the principal element at points which are spaced in opposite directions from the said tie connection in that side-span.

14. Means as in claim 1 for controlling undu-

latory movements, in a structure in which the said supports are towers over which the said principal load-sustaining element extends through side-spans to the said anchorages; in which the harness elements comprise an upper element extending also between and over those towers and through side-spans to anchorages, this harness element being above the principal element between the towers and throughout at least a portion of each side span; there being in each end-quarter-portion of the span between the towers a tie connection of said harness element to the principal element, thereby providing said upward deflections of the principal element; and there

10 being a tie connection of the harness element to the principal element at a mid-location in each side-span, providing there an upward deflection of the principal element; said upper harness element crossing the said principal element in each side-span at a substantial distance from the anchorages, and there being connecting means at that crossing; the anchorages of said harness element being substantially below the respective anchorages of said principal elements, thereby providing downward deflection of the principal element at said connecting means at the crossing; there being in each side span a tie connected to the principal element, extending downwardly obliquely to the tower, providing a downward deflection of the principal element at a point which intervenes between said tie connection and the tower.

15. Means as in claim 1 for stabilizing undulatory movements in a structure in which the said supports are strut members whose top portions are joined by a compression member which is arched at a point in each end-quarter-portion of the span; there being means connecting each said arched point to the principal load-sustaining element beneath it and thereby providing a said upward deflection of that principal element.

16. Means as in claim 1 for stabilizing undulatory movements in a structure in which the said supports are strut members whose top portions are joined by a compression member which is arched at a point in each end-quarter-portion of the span; there being means connecting each said arched point to the principal load-sustaining element beneath it and thereby providing a said upward deflection of that principal element; there being at least two struts between the said compression member and the said principal load-sustaining element; each of these struts being located at the vicinity of the lengthwise middle of one end-half-portion of said span; and there being ties crossing each other between said struts, each of these ties extending from the compression member at the upper end of a said strut to a junction point which is in the principal load-sustaining element and is spaced apart from the bottom of the other said strut and provides a said upward deflection of the principal load-sustaining element at its said junction point.

17. Means as in claim 1 for stabilizing undulatory movements in a structure in which the said supports are strut members whose top portions are joined by a compression member which is arched at a point in each end-quarter-portion of the span; there being means connecting each said arched point to the principal load-sustaining element beneath it and thereby providing a said upward deflection of that principal element, there being at least two struts between the said compression member and the said principal load-sustaining element; each of these struts being lo-

15

16

located at the vicinity of the lengthwise middle of said span; and connected to that principal element one end-half-portion of said span; and there being within each end-quarter-portion of the span, two ties crossing each other between said struts, and another harness element which is located between each of these ties extending from the compression member at the upper end of a said strut to a principal element, having its ends connected to a junction point which is in the principal load-sustaining element at junction points which are in the said harness element and is spaced apart from the bottom within the middle-half-portion of the span, the bottom of the other said strut and provides a said upward deflection of the principal load-sustaining element clamped to the upper element; and tying element at its said junction point; said crossed ties being held together at their crossing, and of the span; having one of these connected to the other there being a tie extending from said crossing to the principal element at a location in that element adjacent to the principal load-sustaining element beneath which intervenes between the connections of the said crossing, providing a said upward deflection of said upper and said other harness elements from that of that element there.

18. Means as in claim 1 for controlling undulatory movements, further characterized in that each of which is nearer to it; each said tie providing, at the principal load-sustaining element has a cross span end portion of the span, a downward deflection of the cross sectional area which is distributed vertically to a junction, intervening between said connections of upper and other harness elements to the principal element to resist downward bending and is distributed horizontally to provide in its lower part a tension carrying area which is greater than that area of upward deflections of the principal element; the said upper part which carries compression; and in each said deflections of the principal element being provided that the said harness-connected points include a said provision when that element is static.

19. Means for controlling undulatory movements of a load-sustaining principal element, each of which is anchored at its ends and hangs with sag to sustain dead load at many points between supports by tension stress existing at least in the lower portion of said element and which stress is transmitted as a tension force to the end anchorages, said principal element being subject to intermittent live loads which tend to produce undulations of that element, said means comprising, in combination, a structure of said principal element in which the cross sectional area is distributed vertically to resist downward bending and is distributed horizontally to provide in the lower part of said element a tension carrying area which is greater than that area of its upper part which carries compression; a stabilizing harness having an upper harness element extending lengthwise of said span above said principal ele-

ment, and a lower harness element at the lower end of each said strut.

MERL R. WOLFARD.
